(74) Attorney, Agent, or Firm — Volpe and Koenig, P.C.

(57) **CLAIM**

The ornamental design for a printing machine, as shown and described.

DESCRIPTION

1. Printing machine

1.1 Perspective view

1.2 Right side elevational view

1.3 Left side elevational view

1.4 Top plan view

1.5 Rear elevational view

1.6 Front elevational view

1.7 Top, right perspective view

1.8 Top, left perspective view

1.9 Front, right perspective view

1.10 Front, left perspective view

1.11 Top, rear perspective view

1.12 Top, front perspective view

1 Claim, 12 Drawing Sheets(56)
